OARS

Ralph E. Franklin, 1818 Queen Ave. N.,
Minneapolis Minn.
Filed Nov. 9, 1959, Ser. No. 851,627
19 Claims. (Cl. 9—24)

This invention relates to boat oars of a radically novel principle which facilitates travel and guiding of a boat particularly when manually powered by an unskilled oarsman.

For centuries oars for rowing a boat have comprised elongated sweep arms having substantially flat, widened blades at the outer portions thereof for engagement with the upper stratum of the water and having intermediate, shouldered fulcrumed portions accommodated in ear locks, tholepins, and the like. The inward portions of the sweep arms constitute handles or grips by which rowing power from the torso and arms is applied. Most oars may be turned or feathered in their mountings to provide for angular adjustment of the blades relative to the water surface both in the "dipping" of the blades preceding a rowing stroke and also for turning of the blades in the "recovery" or forward swinging or skying of the oars preparatory to the next rowing stroke. Accurate "feathering" of oars by hand manipulation and turning to consistently maintain effective angulation of blade to water and for returning or skying the oars requires substantial experience and skill particularly when a boat is rowed in waves and currents. To reduce such difficulties in calm water some oars are now pinned to the oar locks so that blade angulation is preset and so that the oars may not be feathered. However in wind and waves the return stroke of the oars is often very difficult and in the propulsion or rowing stroke the oars often undercut the water making the return stroke difficult and also interfering with proper guidance of the boat by application of more rowing power to one oar than the other.

It is an object of my present invention to provide boat oars which will substantially facilitate rowing particularly by an unskilled oarsman and which in use overcomes the difficulties hereinbefore enumerated.

More specifically it is an object to provide rowing oars which have novel water-engagement elements in lieu of blades, so constructed as to always provide an effective water-engagement or rowing surface without exertion of substantial downward pressure at the outer end of the oars and not requiring feathering or turning of the oars for application of proper and effective strokes.

Another object is the provision of economical and highly efficient oars of the class described wherein a symmetrical and foraminous water-engaging member is provided at the end of each oar offering sufficient resistance to the water while permitting penetration of water therethrough and maintained at an efficient level for beginning of the rowing stroke through buoyant or float means provided in the member to cause adequate water-bridge and surface to be presented below the level of the water regardless of turning of the oar shank in any direction.

A further and more specific object is the provision of an oar having a terminal water-engaging or rowing member which comprises a longitudinal and symmetrical foraminous shell combined with an interior and preferably concentric float member, the specific gravity of the assembly being such as to dispose approximately half of the periphery of the shell below the water level when the oar is at rest and in outstretched position and before any downward or rowing pressure is applied thereto.

These and other objects and advantages of my invention will more fully appear from the following descrip-

2

tion made in connection with the accompanying drawings wherein like reference characters refer to the same or similar views, and in which:

FIG. 1 is an elevational view of one form of my invention in mounted relationship with a boat shown in partial section;

FIG. 2 is a detailed view on an enlarged scale of the water engaging portion of the oar of my invention shown partially in section and partially in elevation;

FIG. 3 is a cross sectional view taken on the line 3—3 of FIG. 2;

FIG. 4 is a detail view of still another form of water-engaging element of the oar of my invention shown on an enlarged scale and shown partially in section and partially in elevation; and

FIG. 5 is a cross sectional view taken on the line 5—5 of FIG. 4.

Reference is now made to the accompanying drawings for a more detailed description of my invention. FIG. 20 shows one form of my invention in which the oar or sweep indicated generally by O is provided with a water engaging portion, element or head A, which oar is pivotally mounted on a boat B by means of a conventional oar lock L, the oar being provided with a suitable conventional leather shoulder or abutment 10, for maintaining the oar in desired position with respect to the boat, the inner end 11 of the oar or sweep constituting a handle or grip by which rowing power is supplied from the rower to the water engaging portion or head A.

30 The water engaging element or head A comprises an elongate preferably symmetrical annular shell 12 having a main body portion corresponding to a truncated cone with the cross section thereof progressively decreasing in size from the inner to the outer end thereof and narrowing from the inner to the outer end of said shell, the outer end of the shell sharply tapering to and terminating in a pointed conical section 13. The head A is tapered as shown in one preferred form of my invention to bring the working edge or side of the head into closer alignment with the water surface for more efficient rowing.

40 The shell 12 of head A is preferably of foraminous material such as expanded metal or screening offering sufficient resistance to the water for propelling the boat being rowed while permitting the penetration and passage of the water therethrough. The shell 12 is corrugated (as best seen in FIG. 3) or provided with a series of generally longitudinally disposed radially extending circumferentially spaced alternate ridges or vanes 14 and depressions 15 around the entire circumference thereof,

50 the corrugated surface providing a greater surface area exposed to the water and offering a greater resistance thereto when moved thereagainst during the rowing stroke. The shell 12 has a hollow sealed tubular member or cylinder 16 disposed concentrically therewith and providing

55 a buoyant float element which is preferably sufficiently buoyant to permit approximately half of the periphery of the water engaging portion or head A to be disposed beneath the surface of the water W under normal conditions with the oar at rest prior to any downward or rowing pressure being applied thereto with approximately the other half of said water engaging portion being disposed above the water level. The head A is provided with a series of radial transversely disposed axially spaced reinforcing members or spiders 17 which in the form

60 shown are disposed adjacent the ends and at the midportion thereof. The head A is provided with a connecting sleeve 18 providing a socket for receiving the outer end 19 of the oar O which is retained therein by any suitable means such as the bolt 19a. The head and handle of the oar are thus fixedly maintained in co-axial alignment with one another, as distinguished from a

65
70

hinged form of my invention hereinafter to be described.

The unhinged form of my invention employing the above described water engaging portion or element A is particularly useful when employed on an oar which is free to rotate in its oar lock as shown in FIG. 1 and whose rotational movements are not confined by any retaining means such as the conventional pins frequently employed to pin the oars to the oar locks to preset the blade angulation and prevent feathering although it is to be understood that the unhinged form shown in FIGS. 1 and 2 is equally effective when pinned to the oar locks for pivotal movement about a horizontal axis. The symmetrical nature of the head A enables the water engaging portion to always be in proper position and present sufficient water engaging or rowing surface at all times thereby avoiding feathering and under-cutting which occurs with conventional type oars. The float 16 causes the oar to automatically adjust itself to the desired depth in the water at the start of each stroke and maintains the proper amount of rowing surface of the oar in the water during the entire stroke, even though the oar should turn or twist in the rower's hand during the stroke. The tapered outer surface of the head A enables the head to assume a stroke relationship with the water engaged therewith more closely approximataely a parallel uniform straight line relationship.

The head C shown in FIG. 4 is similar in principle and function to head A shown in FIGS. 1 and 2 but is designed somewhat differently and is pivotally or hingedly connected to the sweep arm, and is designed for use primarily but not necessarily with oars which are pinned to the oar locks in conventional manner to prevent twisting thereof during use and for presetting the head angulation with respect to the surface of the water. In the form shown in FIG. 4, which is another form of my invention, the head C comprises three concentric generally cylindrical elongate members 20, 21 and 22 respectively reading from the inside member to the outside member, the inner cylinder 20 being sealed at its ends to provide a buoyant float member capable of providing sufficient buoyancy for the head C to maintain approximately half of its periphery out of the water when at rest. The intermediate sleeve 21 and outer sleeve 22 are of foraminous material such as expanded metal, screening or the like and are adapted to provide sufficient rowing resistance to the water engaged thereby while permitting the same to pass therethrough, the outer sleeve 22 acting as the initial water-engager, the intermediate sleeve 21 acting as a secondary water engager. The outer end of the head C is provided with a conical portion or cap 23 similar to conical cap 13 of head A. This form of my invention is also provided with a series of axially spaced radially disposed stiffening or reinforcing members 24 which may take the form of spiders or a solid plate structure. The head C is provided with a sleeve 25 adapted to receive the outer end 19 of the oar in the socket provided therein and fastened therein as by means of the rivet 26. The sleeve 25 is provided with a suitable mounting bracket 27 which is pivotally connected to a suitable mounting bracket or ear 28 as by means of the pin 29, the sleeve 25 and the oar handle carried thereby being capable of being selectively angularly adjustable with respect to the head C and maintained in any given relative angulation by any suitable locking means (not shown). This enables the head C to be angularly preset with respect to the surface of the water according to the individual characteristics of the rower to maintain the head substantially parallel to the surface of the water. The perforations or openings of the intermediate sleeve 21 are preferably smaller than those of outer sleeve 22.

From the foregoing description, the advantages of my invention are readily apparent. The symmetrical annular arrangement and design of the water engaging portion or head enables the rower to repeatedly and uniformly en-

gage the water with a predetermined amount of desirable head surface during the course of his rowing stroke without having to contend with feathering and under-cutting of the terminal portion or water engaging end of the oar even though the oar should turn or twist in his hand while rowing. The float provided in the head prevents the head from sinking and also automatically adjusts the depth of the head so that a proper portion of the water is engaged by the operator during any power stroke thereof. These features are particularly advantageous to the novice rower who is not sufficiently experienced in handling the conventional oar to consistently position the blade to obtain a maximum of rowing efficiency.

It will, of course, be understood that various changes may be made in the form, details, arrangement and proportions of the various parts without departing from the scope of my invention.

What I claim is:

- 20 1. An oar comprising an elongate handle and water-engaging means connected to one end of said handle, said means including a elongate generally cylindrical foraminous annular body member to be disposed generally transversely to the line of rowing movement said body member having openings in the wall thereof communicating with the hollow interior thereof.
- 30 2. The structure set forth in claim 1, including float means concentrically disposed within said member for maintaining said body member at a predetermined depth when dipped in the water.
- 35 3. An oar comprising an elongate handle and water-engaging propulsion means connected to one end of said handle, said means including an elongate perforated annular body member disposed generally transversely to the line of rowing movement and offering rowing resistance to the water engaged thereby while permitting the water to pass therethrough the perforations communicating with the interior and exterior of said body member.
- 40 4. The structure set forth in claim 3 including float means for rendering said body member buoyant and maintaining said body member at a predetermined angle and depth with respect to the water line when afloat in the water.
- 45 5. An oar comprising an elongate handle and water-engaging means connected to one end of said handle, said means including an elongate body member having a pair of substantially concentric foraminous tubular elements disposed one within the other providing substantial resistance to the water when moved thereagainst while permitting the passage of the water therethrough.
- 55 6. The structure set forth in claim 5, including a sealed tubular float member enclosed within the inner foraminous tubular element and rendering the body member sufficiently buoyant to maintain said member at a predetermined angle with respect to the surface of the water.
- 60 7. An oar comprising an elongate handle and water-engaging means connected to one end of said handle, said means including an elongate foraminous annular body member corrugated in cross section, and a water tight float element disposed within said body member adapted to maintain said body member at a predetermined level with respect to the surface of the water the perforations in said body member communicating with the hollow interior thereof.
- 65 8. Oar structure comprising an elongate handle portion having water engaging propulsion means mounted on the outer end thereof, said means including a downwardly facing generally convexly curved foraminous water engaging shell portion whose axis of curvature extends generally transversely of the direction of rowing movement and which presents a curved foraminous working face to the action of the water during rowing the foraminous shell having openings communicating with the hollow interior thereof.
- 70 9. Oar structure comprising an elongate handle por-

tion having water engaging propulsion means mounted on the outer end thereof, said means including an annular generally cylindrical foraminous shell, and a series of generally radially extending circumferentially spaced apart rib means symmetrically disposed about the axis of said shell providing a uniformly corrugated exterior, said foraminous shell extending between and interconnecting the outer end portions of said ribs the foraminous shell having openings communicating with the hollow interior thereof.

10. An oar comprising an elongate handle and water engaging means connected to one end of said handle, said means including an elongate foraminous annular shell substantially symmetrically arranged about its longitudinal axis and presenting substantially similar water surface portions about the entire periphery thereof, and a second foraminous annular shell mounted substantially concentrically within said first named shell, the openings in said second shell being smaller than those in said first named shell.

11. In oar structure, propulsion means for mounting on the handle of the oar, said propulsion means comprising a downwardly facing hollow water engaging shell having generally opposed spaced apart foraminous wall portions normally disposed generally transversely of the direction of movement, said foraminous wall portions constituting the primary propulsion medium for said oar.

12. In oar structure, propulsion means for mounting on the handle of the oar comprising a hollow water engaging foraminous shell disposed transversely of the direction of movement whereby the water enters the hollow interior of said shell through one foraminous portion thereof and is discharged from said interior through another foraminous portion thereof.

13. In oar structure, propulsion means for mounting on the handle of the oar comprising a hollow water engaging foraminous walled shell disposed transversely of the direction of movement, the openings in the wall of the shell communicating with the interior thereof.

14. Oar structure comprising an elongate handle having propulsion means mounted on one end thereof, said propulsion means comprising a hollow foraminous walled shell disposed transversely of the direction of movement, the foraminous wall portions of said shell constituting the

primary propulsion medium for said oar, the openings in said wall portions communicating with the hollow interior of the shell.

15. An oar comprising an elongate handle and water engaging means connected to one end of said handle, said means including an elongate foraminous annular shell substantially symmetrically arranged about its longitudinal axis and presenting substantially similar water surface portions about the entire periphery thereof, the foraminous portions of said shell constituting the primary propulsion portion for said oar, the openings in said portions communicating with the interior of said shell.

16. The structure set forth in claim 15, including float means for floating said shell at a predetermined depth in the water.

17. The structure set forth in claim 15, wherein said shell is generally conical in form with the cross section of said shell progressively decreasing in size from the inner to the outer end thereof.

18. The structure set forth in claim 15, wherein said shell includes a series of generally longitudinally disposed generally radially extending circumferentially spaced raised portions providing resistance to the movement of said shell through the water.

19. In oar structure, propulsion means for mounting on the handle of the oar, said propulsion means comprising a hollow shell constituting the primary propulsion medium for said oar, said shell having a multiplicity of small openings formed therein over substantially the entire periphery thereof which communicate with the interior of said shell.
